UNITED STATES PATENT OFFICE.

OTTO W. LUNDHOLM, OF DES MOINES, IOWA.

AUTOMATIC MINE-DOOR.

SPECIFICATION forming part of Letters Patent No. 793,452, dated June 27, 1905.

Application filed June 1, 1904. Serial No. 210,683.

To all whom it may concern:

Be it known that I, OTTO W. LUNDHOLM, a citizen of the United States, residing at Des Moines, in the county of Polk and State of Iowa, have invented a certain new and useful Improvement in Automatic Mine-Doors, of which the following is a specification.

The objects of my invention are to provide an automatic trap-door especially designed for use in mines to prevent the escape of air from the mines and to automatically open and close when a mine-car approaches and passes beyond the same, and, further, to provide means for automatically locking the doors in their open position, so that air-currents will not swing them when a car is passing through a door-opening.

My invention consists in certain details in the construction, arrangement, and combination of the various parts of the door and door-operating mechanism, as hereinafter more fully set forth, pointed out in my claims, and illustrated in the accompanying drawings, in which—

Figure 1 shows a perspective view of the complete door and door-operating mechanism, showing the door in its closed position. Fig. 2 shows a top or plan view of same with the door in its open position. The dotted lines indicate the closed position of the door. Fig. 3 shows a side elevation of the complete mine-door and connected parts. The dotted lines in this figure indicate the open position of the door and the arrangement of the operating mechanism and lock when the door is open. Fig. 4 shows an end view of a mine-car upon a track and the lever by which the door is operated in its position adjacent to the car-wheel. Fig. 5 shows a perspective view of the lever for operating the mine-door and connected parts, and Fig. 6 shows a detail sectional view of part of one of the mine-doors and the lever connected therewith by which the door is opened and closed.

Referring to the accompanying drawings, I have used the reference-numeral 10 to indicate a framework to be placed in a mine-entry at the point where the door is to be located. The numeral 11 indicates a railway-track running through the said frame.

The door proper is composed of two door-sections, in their closed position arranged at about right angles to each other. The meeting edges of the door-sections project in the direction of the interior of the mine. These 55 door-sections are indicated by the numeral 12 and each is provided with a handle 13 near its inner edge. The door-sections are pivotally supported at their upper ends by the pins 14, which are mounted in suitable bearings in the 60 frame 10, and at their lower ends by the pins 15, which are supported in brackets 16 at the bottom of the mine-entry.

The upper and lower pins of each door-section are in line with each other and are arranged nearer to the outer end of the section than to the inner end. This is done for the reason that the air-pressure upon the inner end portions of the door-sections will be greater than upon the outer end portions, so 70 that this air-pressure itself serves to hold the door-sections firmly together, and yet a part of the air-pressure is thrown upon the outer portion of the door-sections, so that comparatively little power is required to overcome the 75 air-pressure when it is desired to open the door. In this connection I have provided means whereby the quantity of air escaping through the doorway when the door is open is reduced to a minimum, as follows: The numeral 17 indicates a stationary partition arranged adjacent to the outer end of each door-section and extending from the top to the bottom of the mine-entry and from the side walls inwardly to a point adjacent to the track 11, 80 and the inner edge of said partition is arranged to be engaged by the outer edges of the adjacent door-sections when the door-section is open, as clearly shown in Fig. 2, thus preventing the passage of air through the 85 doorway outside of the doors and permitting the air to pass through the doorway only through the space between the doors when they are open.

I have provided for opening and closing the 95 door as follows: The numeral 18 indicates a rock-shaft, mounted in suitable supportings beneath the door and provided with arms 19 at its ends. At the top of each of the arms 19 is a pivoted bracket 20, which bracket is 100

connected to a bracket 21 on the adjacent door-section by means of link 22. Hence when the shaft 18 is rocked in a direction to throw the arm 19 rearwardly toward the door-section the said door-section will be opened, because the brackets 21 are fixed to the door-sections outside of their pivotal centers, and when their arms 19 are moved in the opposite direction the doors will be closed. On 5 one end of the shaft 18 I have fixed an arm 23, having a pin 24 fixed to its upper end, and the numeral 25 indicates a link provided with slots 26 at its sides, through which the said pin 24 is passed, thus permitting the link to 10 move longitudinally a limited distance before moving the arm 23. Connected to the upper end of the arm 23 is a bracket 27, in which I have pivoted a bell-crank lever 28, the upper end of which passes through the link 25. The 15 numeral 29 indicates a rod pivoted at its upper end to the lower end of the bell-crank lever 28. Near the lower end of the rod 29 is an extension 29^a, which is slidingly held to the arm 23 by the bracket 29^b. The lower 20 end of the rod 29 is beveled. By this construction it is obvious that when the link 25 is moved in one direction the lever 28 will be tilted to move the rod 29 downwardly and when the link 25 is moved in another direction 25 said rod will be elevated relative to the arm 23. In Fig. 3 the solid lines show the rod 29 elevated and the dotted lines show it lowered. The numeral 30 indicates a bracket fixed to a stationary support adjacent to the lower end of the arm 23, and said bracket is 30 provided with a lug 31. This lug is so positioned that when the arm 23 is moved to its limit toward the door the lower end of the rod 29 will engage the lug 31 and lock the arm 23 35 against movement in the opposite direction, and said arm 23 can be moved in a direction away from the door only if the link 25 has been moved as required, to elevate the rod 29. When the arm 23 is moved to its limit toward the 40 door by means other than that imparted by the link 25, then the rod 29 does not engage the lug 31. This is desirable for the following reasons: When the door is opened or closed automatically by a car, then the link 25 is always operated before the arm 23 is moved. Hence 45 when the door is opened it will be locked in this position, so that it cannot swing when a car is passing through the door-opening; but when a door is opened by hand—as, for instance, when a person desires to walk through a door-opening—then the link 25 is not operated first, and the door may be opened either partly or wholly by hand and closed by hand without being locked in its open position, for 50 if it were locked it could be opened only by the operator passing to the nearest lever designed to engage a car-wheel, and this operation would take considerable time and leave the door open longer than necessary. I have provided 55 for operating the link 25 in the proper direc-

tion for opening and closing the door when a car approaches or passes beyond the door in either direction, as required, to first open and then close the door, as follows: At a suitable distance from the door on either side are the 70 uprights 32, in each of which I have mounted a rock-shaft 33. On one end of each rock-shaft 33 is a lever 34. Attached to the top of one of the levers 34 is a wire or cable 35, the other end of which is attached to the lower end of the opposite lever 34, and attached to the lower 75 end of the first lever 34 is a wire or cable 36, attached to the adjacent end of the link 25, and a similar wire or cable 37 is attached to the other end of the link 25 and to the top of 80 the other lever 34, as clearly shown in Fig. 3. Fixed to the inner end of each of the rock-shafts 33 is a slotted segmental guide 38, and pivotally mounted on the same end of the shaft 85 is a trip-arm 39, the upper end of which projects through the slot in the guide 38 and the lower end of which projects downward in position to be engaged by a car-wheel passing over the track 11. The lower end of the arm 39 is materially heavier than the upper end, 90 and hence always hangs straight downward except when moved by the passing car-wheel.

In practical use and assuming that a car is approaching the closed door from the side toward which the door-sections project—as, for instance, from the left in Fig. 1—the first car-wheel will strike upon the arm 39 and push it toward the door, thus moving the guide 38 away from the door, because the upper end of arm 39 will be in engagement with the end of the slotted guide farthest away from the door. This will rock the shaft 33 as required to move the upper end of the adjacent lever 34 away from the door. This movement will cause the wire or cable 35 to pull the lower end of the 100 opposite lever 34 toward the door, thus throwing the upper end of the said opposite lever away from the door and moving the link 25 toward the door. The first effect of this movement of the link 25 toward the door will be 105 to release the bell-crank lever 28 and permit the rod 29 to engage the lug 31. The further movement of the link 25 will then move the arm 23 toward the door, thus rocking the shaft 18 and causing the arms 19 to push the outer 110 ends of the door-sections in the direction required for opening the door-sections, and when the door-sections are open the bolt 29 drops by gravity behind the lug 31, thus locking the door-sections in their open position. 115 When the car has passed through the door, it will engage the arm 39 at the opposite side of the door and move the link 25, as required, first to release the bolt 29 and then to swing the door-sections to their closed positions. 120 In this way the door-sections are automatically opened by a car approaching from either direction, then automatically locked in their open position, and finally released and closed as the car passes beyond the door. 125

When a person approaches the door from the side toward which the door-sections are projecting, he may open them easily by grasping one of the handles 13 and may then pass 5 through the door and close it by hand without having the door locked. Furthermore, when the doors are closed the air-pressure from the inside of the mine-entry will tend to hold them closed to prevent leakage of air o through the door-opening, because the preponderance of surface of the door-sections is exposed to the air-pressure, and yet the door-sections may be easily opened, because there is considerable air-pressure on the outer ends 5 of the door-sections. Furthermore, by providing the partitions 17 the air is prevented from passing through the entry outside of the door-sections when they are open, and this air-pressure is prevented from moving or o closing the door-sections when they are in their open positions on account of the automatic lock.

Having thus described my invention, what I claim, and desire to secure by Letters Patent of the United States therefor, is—

1. The combination of two door-sections, in their closed positions standing approximately at right angles to each other and means for pivotally supporting each of said door-sections at its upper and lower ends at points between its center and outer end, and stationary partitions arranged to engage the outer ends of the door-sections when said sections are in their open positions.

35 2. The combination of a door-frame, two door-sections pivotally mounted in the frame to swing in horizontal planes, and stationary partitions arranged to stand adjacent to the outer ends of the said door-sections, when in o their open positions.

3. The combination of a door, a rock-shaft, a slotted segmental guide fixed to one end of the shaft, an arm pivotally mounted on the shaft with one end in the slotted guide, a lever fixed to the shaft and means connected 45 with the lever for operating the door.

4. The combination of a door, two rock-shafts pivotally supported at opposite sides of the door, each having a segmental slotted 50 guide fixed to one end, an arm pivoted to the same end with one end in the slotted guide, and a lever fixed to the other end, means for connecting the lower end of one of said levers with the upper end of the other, means for connecting the upper end of the first-mentioned lever with the lower end of the other, and means operating by one of said connecting means for opening and closing the door.

5. The combination of two door-sections each

pivotaly supported at its upper and lower 60 ends, a rock-shaft mounted beneath the door-sections, an arm fixed to each end of said rock-shaft, a bracket pivoted to each arm, a link pivoted to each bracket, and to the adjacent door-section, and means for rocking said shaft 65 to open and close the door-sections.

6. The combination of two door-sections each pivotally supported at its upper and lower ends, a rock-shaft mounted beneath the door-sections, an arm fixed to each end of said rock-shaft, a bracket pivoted to each arm, a link pivoted to each bracket, and to the adjacent door-section, means for rocking said shaft to open and close the door-sections, and means for automatically locking the rock-shaft when 75 the door-sections are in their open positions.

7. The combination of two door-sections each pivotally supported at its upper and lower ends, a rock-shaft mounted between the door-sections, and an arm fixed to each end of said 80 rock-shaft, a bracket pivoted to each arm, a link pivoted to each bracket, and to the adjacent door-section, means for rocking said shaft to open and close the door-sections, means for automatically locking the rock-shaft when the 85 door-sections are in their open positions, said means comprising an arm fixed to the rock-shaft a slide-rod mounted on said arm, a bracket secured to a stationary support and provided with a lug to be engaged by the 90 slide-rod when the door-sections are open, and means for jointly operating the said arm and slide-rod.

8. The combination of two door-sections pivotally supported at their upper and lower ends, 95 a rock-shaft beneath the door-sections, arms at the ends of the rock-shaft, means for connecting said arms with the door-sections, an arm fixed to one end of the shaft, a bell-crank lever pivoted to said arm, a slide-rod pivoted 100 to the bell-crank lever, a stationary lug to be engaged by the slide-rod, a link slidingly mounted at the upper end of said arm and having slotted sides, a pin mounted in the arm and passing through the slotted sides, said 105 links when moved in one direction first operating the bell-crank lever to elevate the slide-rod and then moving the arm, and said link when moved in the opposite direction first releasing the bell-crank lever to permit the slide-rod to descend and then operating the arms, and means actuated by a vehicle for moving 110 said link substantially as and for the purposes stated.

OTTO W. LUNDHOLM.
